UNITED STATES PATENT OFFICE.

WILLIAM METZROTH, OF MIDDLETOWN, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,139,890.

Specification of Letters Patent. Patented May 18, 1915.

Application filed April 23, 1910. Serial No. 557,131.

To all whom it may concern:

Be it known that I, WILLIAM METZROTH, a citizen of the United States, residing at Middletown, in the county of Middlesex and State of Connecticut, have invented certain new and useful Improvements in Type-Writing Machines, of which the following is a full, clear, and exact description, such as will enable others skilled in the art to 10 which it appertains to make and use the same.

This invention relates to ribbon mounting mechanism for typewriting machines, and with regard to the more specific features 15 thereof to the ribbon spool and cup.

One of the objects of the present invention is to provide a simple and practical ribbon spool and cup of improved form and construction.

20 Another object is to provide a construction of the above character which will be cheap to manufacture and efficient in operation.

A further object is to provide an improved 25 form of ribbon spool and cup for preventing displacement of the ribbon.

A further object is to provide mechanism of the above character to prevent the ribbon from slipping between the ribbon spool and the cup surrounding same.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claims.

40 In the accompanying drawing, wherein is shown one of many possible embodiments of my invention, Figure 1 represents a vertical sectional view of a part of the ribbon supporting mechanism of a typewriting machine sufficient to illustrate the present embodiment of the invention; Fig. 2 is a detail view of one of the parts.

Similar reference characters refer to similar parts throughout both views of the drawing.

50 While the present invention is herein

shown and described with reference to a ribbon spool or reel and cup adapted to be used with a narrow ribbon in a visible writing machine, and particularly the ribbon 55 mounting of that style used in the noiseless typewriting machine, it is, of course, to be understood that it may be used on other forms of typewriters as well.

Referring to this drawing in detail, 1 denotes the ribbon spool spindle adapted to be driven by any suitable mechanism (not herein shown) for feeding a ribbon 2 past the printing point to a corresponding spool at the opposite side of the machine in a well known manner. This ribbon 2 may be secured to a ribbon core 3 in any suitable manner to be slipped on a hollow cylindrical hub 4 of the ribbon spool loosely mounted on the spindle 1. This hub 4 is adapted to 60 be driven through suitable gearing, 5, 6 and 7, the gears 5 and 7 being respectively loose and fast on the spindle 1, while the gear 6, adapted to mesh with both gears 5 and 7, is thrown into and out of engagement therewith by mechanism not herein shown as it forms no part of this invention, for the purpose of reversing the ribbon feed. The hub 4 of the ribbon spool is provided with a ribbon supporting flange 8 rotatable therewith 65 and upon which the ribbon is wound, fitting within a ribbon cup or container 9, secured to the frame of the machine by means of a screw 10. This cup comprises a stationary wall and a slight space is preferably provided between the outer edge of the rotating ribbon supporting flange 8 of the spool and the cup to prevent friction between these parts when one is rotating relatively to the other.

When the flanges are accurately machined to fit and rotate in the cup, there is necessarily a space between the edge of the flange and the cup, and the ribbon is liable to slip into this space, causing trouble in the operation of the parts. When the flanges are stamped out in large quantities from sheet metal, which is the preferable commercial method of their manufacture, the space between the edge of the flange and the cup is 90 sometimes larger. In either case it is desirable to avoid the ribbon entering the space

thus formed, and to this end a shield is located in a position overhanging the space by providing a grooved recess in the cup 9 adapted to be engaged by a ring 11, shown in detail view Fig. 2. This ring, being preferably split and of resilient material, snaps firmly into place and shields or protects the opening in the manner shown, and may be removed by the aid of a knife or other sharp pointed instrument when it is desired to remove the spool for any reason, after first removing a ribbon spool cover 12 suitably connected with the spindle 1 for the purpose of protecting the ribbon and preventing the same from riding up over the edge of the cup instead of passing through a slot 13 provided therefor to the printing point.

It is thus seen that this invention provides for a simple practical device attaining, among others, the objects and advantages above set forth, and adapted to hold the ribbon in place as the same is wound or unwound upon the spool, and prevent the same from falling between the spool and the cup and becoming entangled with the driving mechanism for the spool therebeneath.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as now and desire to secure by Letters Patent is:

1. In a ribbon mounting, in combination, 40 rotatable means adapted to support a ribbon, a wall extending opposite a portion of said means adapted to confine the ribbon and permit rotation of said means, and a guard adapted positively to protect the ribbon from becoming disposed between said means and said wall while said means rotates.

2. In a ribbon mounting, in combination, 50 rotatable means adapted to support a ribbon, a wall extending opposite a portion of said means adapted to confine the ribbon and permit rotation of said means, and means adapted to guard said ribbon from becoming disposed between said rotatable means and said wall and simultaneously secure said member against displacement with respect to said cup.

3. In a ribbon mounting, in combination, 60 a fixed circumferential wall, means adapted to support a ribbon comprising a member disposed for rotation within said wall, and means comprising an arcuate guard detachably secured to said wall adapted positively to protect the ribbon from becoming dis-

posed between said member and said wall while said member rotates.

4. In a ribbon mounting, in combination, 70 a fixed circumferential wall, means adapted to support a ribbon comprising a member disposed for rotation within said wall, and means comprising an arcuate uncontinuous guard adapted to protect the ribbon from becoming disposed between said member and said wall while said member rotates.

5. In a ribbon mounting, in combination, 75 a ribbon cup, means comprising a member disposed for rotation in said cup adapted to support a ribbon, and means comprising an arcuate guard detachably secured to said cup adapted to guard said ribbon from becoming disposed between said member and the inner peripheral wall of said cup and simultaneously secure said member against displacement with respect to said cup.

6. In a ribbon mounting, in combination, 80 a ribbon, a ribbon cup having an annular recess, a ribbon spool within said cup and resilient means adapted to be sprung into said recess to protect the space between the spool and cup for preventing the ribbon 90 from slipping therebetween.

7. In a ribbon mounting, in combination, 95 a ribbon, a ribbon cup having an annular recess, a ribbon spool within said cup, and a removable annular resilient ring adapted to be sprung into said recess to protect the space between the spool and cup for preventing the ribbon from slipping therebetween.

8. In a ribbon mounting, in combination, 100 a ribbon, a ribbon cup, a rotatable ribbon reel therein, and annular means mounted on said cup adapted to protect the intervening space between the cup and reel for preventing the ribbon from falling between adjacent parts of said cup and reel.

9. In a ribbon mounting, in combination, 105 a ribbon, a driving spindle, a ribbon cup, a ribbon spool on said spindle and adapted to be driven thereby, a supporting flange on 110 said spool rotating within said cup, and annular means embedded in the inner side of said cup adapted to cover the space between the cup and flange.

10. In a ribbon mounting, in combination, 115 a ribbon, a driving spindle, a cup, a spool loosely mounted on said spindle within said cup; means for operatively connecting said spool with said spindle, a removable cover for said spool, a flange rotatable with said spool on which the ribbon is adapted to be wound, said cup having a recess, and a ring adapted to engage said recess and protect the space between the said flange and cup for preventing the ribbon from slipping 120 therebetween.

11. In a ribbon mounting, in combination, 125 a ribbon, a driving spindle, a cup, a spool

loosely mounted on said spindle within said cup, means for operatively connecting said spool with said spindle, a removable cover for said spool, a flange rotatable with said spool on which the ribbon is adapted to be wound, said cup having a recess, and an annular resilient removable ring adapted to engage said recess and protect the space be- tween the said flange and cup for preventing the ribbon from slipping therebetween. ¹⁰
In testimony whereof I affix my signature, in the presence of two witnesses.

WILLIAM METZROTH.
